UNITED STATES PATENT OFFICE.

GLENN A. KNAPP, OF PUEBLO, COLORADO.

PENCIL-HOLDER.

1,277,732.

Specification of Letters Patent. Patented Sept. 3, 1918.

Application filed December 27, 1917. Serial No. 209,114.

To all whom it may concern:

Be it known that I, GLENN A. KNAPP, citizen of the United States, residing at Pueblo, in the county of Pueblo and State 5 of Colorado, have invented certain new and useful Improvements in Pencil-Holders; and I do hereby declare the following to be a full, clear, and exact description of the invention, such as will enable others skilled 10 in the art to which it appertains to make and use the same.

This invention relates to pencil holders, readily attachable and detachable to fabric material such as the vest or coat, or other 15 piece of wearing apparel of an individual.

It is one of the objects of the present invention to provide an extremely simple, practicable, inexpensive, and reliably acting device for readily receiving and holding 20 pencils or the like, so that they may be conveniently at hand for use when desired. Another object of the invention is to provide a pencil holder with its parts so constructed that they automatically retract, and 25 it is further a purpose of the invention to provide means for automatically setting the hooks of the device so that danger or injury to the user may be eliminated as far as possible, and another object of the invention is 30 to provide a device of this type of few, simple, and therefore inexpensively manufactured parts, and one which may be readily applied.

With the above and other objects in view 35 as will be rendered manifest, the invention consists in the whole, the construction, the combination, and in details and arrangements of the elements as more particularly described hereinafter, one embodiment of 40 the invention being illustrated in the accompanying drawing in which:

Figure 1 is a perspective of the device as applied and in use.

Fig. 2 is a front perspective of the device 45 with the pencil removed.

Fig. 3 is a perspective of the rear of the device.

Fig. 4 is a longitudinal central section 50 through the holder, showing the normal retracted position of the hooks.

Fig. 5 is a similar section showing the hooks as substantially projected for engagement with the garment, a portion of which is shown in dotted lines.

Fig. 6 is a perspective of the connected 55 hooks removed from the shell.

Fig. 7 is a plan view of the shell before it is folded.

Fig. 8 shows detailed views in plan and side elevation of the detached upper hook. 60

In the embodiment of the invention here shown, a shell of sheet metal or other suitable material, which may be folded up from a blank indicated in Fig. 7 at B, comprises an integral back structure 2 with marginal 65 side leaves 3-3, which are shown as of curvilinear outline, these being adapted, when rolled into tubular form, to produce in front of the back 2, as shown in Fig. 2, a chamber into which may be readily inserted a pen holder, pencil, or other similar articles to be held, the upper edge of the back 2 being provided with a lip 4 extending forwardly having a straight edge 5, against which the body of the pen holder or pencil 70 will rest while the lower end of the pencil will be supported against a lower lip edge, formed by overlapped tongues 6-6, which, when folded together, form an aperture 7 in line with a longitudinal recess 8, extending 75 up the back 2.

For the purpose of readily connecting the shell or holder to the fabric or piece of wearing apparel to which the holder is to be attached, there projects through the aperture 85 in this form, at the bottom of the shell a hook pin 10, the point 11 of which is disposed to project rearwardly from the back of the plane and reacting between the lip 6 and the head 12 of the pin 10, there is a coil 90 spring 13 which automatically acts to contract the hook 11 upwardly toward the bottom of the shell. The coil spring 13 occupies a position in the longitudinal recess or groove 8 in the back of the shell. In the upper end in the back of the shell, which is inclined forwardly and upwardly at the plane 2¹, are provided apertures 14, through which project downwardly directed hooks 15 which are here shown as having integral connected shanks at 16, bent in the form of the letter V, and to the crotch of the bent shanks there is provided a connection between the upper hooks and the pin 10. It is desirable 95 that the upper hooks 15 be automatically thrown or set, when disengaged, in proximity to the inclined plane 2, or at the top of the back, so that the retracted pins may be held in such position as to avoid accidental hooking or injury to adjacent objects or the user. To accomplish this, the

spring 13 is shown as extended above the 100 105 110

head 12 of the pin and connected to the crotch of the shanks 16, the length and angular disposition of this extension 13^a of the spring tending to pull the hooks outwardly 5 against the upper portion of the back 2.

In the application of the device, the user simply presses the shell against the surface of the garment with an upward movement so that the hook 11 is caused to move downwardly and compress the spring 13, which places the flexible connection 13^a under tension, and thus pulls down or locks the lever-shaped hooks 15 in their bearings at the apertures 14, causing them to assume the position shown in Fig. 5, and enables them to be readily pressed into the garment material, whereupon, by releasing the shell, the hooks 11 and 15 again contract relatively, and firmly attach themselves and the holder to 20 the garment.

Having described my invention, what I claim and desire to secure by Letters Patent is:

1. A pencil holder adaptable for attachment to fabric material, comprising a shell having yieldable front leaves forming a chamber for a pencil, a hooking device pivoted in the upper end of the shell and projecting to the rear thereof, and a rear hook 30 at the bottom of the shell.

2. A pencil holder adaptable for attachment to fabric material, comprising a shell having yieldable front leaves forming a chamber for a pencil, a hooking device pivoted in the upper end of the shell and projecting to the rear thereof, and a rear hook 35 at the bottom of the shell, said hooks being yieldingly connected.

3. A pencil holder adaptable for attachment to fabric material, comprising a shell having a pair of complementary yieldable leaves to embrace a pencil, the upper and lower ends of the shell having forwardly extending lips against which the pencil is held 45 by the leaves.

4. A pencil holder adaptable for attachment to fabric material, comprising a pencil receiving shell, and yieldingly connected

hooks at opposite ends of and extending rearwardly through the shell.

5. A pencil holder adaptable for attachment to fabric material, comprising a pencil receiving shell, and yieldingly connected hooks movably supported in opposite ends of the shell.

6. A pencil holder adaptable for attachment to fabric material, comprising a receiver, hooks mounted on the receiver ends, and flexible means extending along the receiver for contracting the hooks.

7. A pencil holder adaptable for attachment to fabric material, comprising a shell having a longitudinally grooved back, and front resilient leaves to embrace a pencil, a spring seated on the lower end of the shell 65 and lying in the groove, a pin supported by the spring and having a hook in front of one end of the shell, a hook pivoted in the opposite end of the shell back, and connected to said pin.

8. A pencil holder adaptable for attachment to fabric material, comprising a shell having a longitudinally grooved back, and front resilient leaves to embrace a pencil, a spring seated on the lower end of the shell 75 and lying in the groove, a pin supported by the spring and having a hook in front of one end of the shell, a hook pivoted in the opposite end of the shell back, and connected to said pin by an extension of said 80 spring.

9. A pencil holder adaptable for attachment to fabric material, comprising a shell having a longitudinally grooved back, and front resilient leaves to embrace a pencil, a spring seated on the lower end of the shell 85 and lying in the groove, a pin supported by the spring and having a hook in front of one end of the shell, a hook pivoted in the opposite end of the shell back, and connected to said pin by an extension of said spring, 90 said extension tending normally to retract the hook.

In testimony whereof I affix my signature.

GLENN A. KNAPP.
